UNITED STATES PATENT OFFICE.

CHARLES A. BRUST, JR., OF EL DORADO, ARKANSAS.

WELL FISHING TOOL.

Application filed November 6, 1922. Serial No. 599,357.

To all whom it may concern:

Be it known that I, CHARLES A. BRUST, Jr., a citizen of the United States, residing at El Dorado, in the county of Union and State of Arkansas, have invented certain new and useful Improvements in Well Fishing Tools; and I do declare the following to be a full, clear, and exact description of the invention, such as will enable others skilled in the art to which it appertains to make and use the same.

This invention relates to what may be conveniently termed a combination well tool due to the fact that it is capable of serving two separate uses, namely, as a well fishing tool and as a tubing catcher.

It is an object of the invention to provide a unique tool of this class which embodies, among other details, a tubular carrier for a plurality of friction balls, a cone for forcing these balls into tight engagement with a casing, tubing, or other implement to be removed from the well, and spring means for floating this carrier and disposing it in a position to insure a rapid and positive grip of the balls.

More specifically, it is another object of the invention to provide a unique tubing catcher for permanent installation in the well, the same embodying a coupling for two of the sections of the tubing and this coupling having a portion of its exterior designed to form a conical expander for friction balls which are supported in a floating position by a unique means which insures a rapid and effective grip of the balls with the conical expander and stationary well casing to prevent dropping of the tubing should it become accidentally disconnected from the hoisting means.

Other objects and advantages of the invention will be apparent during the course of the following description.

In the accompanying drawings forming a part of this specification and in which like numerals are employed to designate like parts throughout the same:

Figure 1 is a central vertical sectional view, with parts in elevation, of a tool constructed in accordance with this invention showing the same in a gripping position at the center of a section of the well casing to prevent dropping of the tubing.

Fig. 2 is a horizontal section taken on the line 2—2 of Fig. 1.

Fig. 3 is a view like Fig. 1, showing the

parts inverted to disclose the manner of using the tool for fishing.

Fig. 4 is a vertical section similar to Fig. 3, showing a different position of the tool when used for the last named purpose.

Fig. 5 is a horizontal section taken on the line 5—5 of Fig. 3.

As before intimated, the invention resides in a combination tool which provides either a fishing tool or a well tubing catcher. As particular emphasis is to be laid on the use of the tool for catching tubing, the detailed description will first be confined to Figs. 1 and 2 of the drawings.

By directing attention to these figures, it will be seen that the letter "C" designates the usual stationary well casing and "A" refers generally to the tubing in which the usual plunger (not shown) is slidable. As customary, the tubing is composed of a plurality of lengths or sections "S". As is well known, the entire tubing in a well must be frequently removed for the purpose of repairing the pipes and other parts of the plunger. As the tubing is of considerable length and extremely heavy, it often happens that the hoisting means fails to operate and the tubing is accidentally dropped into the well, thus crushing the sections and practically destroying the entire well. In view of this disadvantage it is proposed to permanently install unique means in the well which is such as to absolutely prevent the tubing from dropping in the event that it is accidentally released by the hoisting means.

As seen, the preferred structure comprises a comparatively large coupling 11 which is connected with the adjacent ends of two of the sections of the tubing as illustrated.

In practice, any number of such couplings may be used. Each coupling is preferably a heavy casting and in order to permit it to function in the manner described, it is formed on its exterior adjacent one end with a substantially conical portion 12 which constitutes an expander. The coupling is internally screw-threaded at its opposite ends to permit connection of the sections S of the tubing and is decreased in diameter intermediate its ends to provide a shoulder 13 against which the inner ends of the sections of the tubing abut. The intermediate diameter of the coupling is the same as that of the internal diameter of the tubing. As before intimated, a plurality of friction gripping balls 14 are used in connection with the expander

cone 12 and they are supported in a position to be in constant contact therewith through the medium of a substantially cup-shaped carrier 15 which is formed at its upper end with a plurality of circumferentially spaced openings 15^a in which the balls are positioned. The walls of the several openings are inclined as shown to limit the outward movement of the balls. The lower end 10 of the carrier is flattened as indicated at 16 and one end of a coiled spring 17 abuts this flattened end. The spring 17 surrounds the section of the tubing as shown and the opposite end thereof abuts a small 15 and conventional coupling 18. The tension of this spring is such as to support the carrier and balls in a floating position which is such as to render the balls readily susceptible to gripping the conical expander at the inner wall of the well chamber in the event that the tubing accidentally falls.

In practice, one or more of the devices is installed in the well at the time of construction and permanently left in position so that 25 they will come into play in the event that the tubing should be accidentally lost while hoisting it to make repairs. It is clearly obvious that should the tubing drop, the coupling 11 will move downwardly while the ball carrier 30 15 will momentarily remain stationary, due to the tendency of the spring 17 to expand. This being the case, the conical expanding surface 12 will act on the friction balls 14 to force them radially outward and into 35 tight frictional engagement with the inner wall of the well casing. Since the latter is stationary, it is evident that further descent of the tubing will be prevented.

Referring now to Figs. 4 to 6, wherein another use of the invention is illustrated, it 40 will be seen that the numeral 1 designates generally a longitudinally bored body formed at its lower end with a conical portion 2 which serves a purpose to be herein-after described. Threaded into the opposite ends of the bore of this body are pipes 3 and 4 respectively, the upper one of which constitutes a guide for an inverted cup-like carrier 5 which is slidable thereon. As 45 seen, the lower end of this carrier is equipped with a plurality of closely spaced circumferential openings 6 through which friction balls or the like 7 are projected through the medium of the aforesaid cone 2. 50 The openings are of such design as to limit the outward expansion of the balls.

Although the carrier 5 could itself serve to move the balls 6 downwardly on the conical surface 2 to expand them into engagement with the tubing T, it is desired to provide means which will assist in accomplishing this end so as to insure positive action of the balls. The preferred means comprises a coiled spring 8 which surrounds the aforesaid pipe 4 between the closed end of the

carrier 5 and a coupling 9 which is connected with the upper end of the pipe. The coupling is thus permitted to function as a shoulder for the spring and also as means for permitting connection of the lowering pipe 10.

In operation, the tool is lowered into the well by the usual lowering means which is connected with the coupling 9 as before inferred. Since the tool is especially designed for gripping tubes and casings, it will be seen that as it enters the upper end of the tube, the edge of the latter will serve to lift the carrier 5 against the action of the spring in a manner to permit the gripping balls 7 to move inwardly. Then, the tool will slip freely down through the tube to the desired point. As soon as the tool is lifted, the conical surface 2 of the aforesaid body will serve to force the balls outwardly through the openings 6 into frictional engagement with the inner wall of the tubing T. Hence, the tool will be locked to the latter and the removal effected. Attention is directed to the fact that the spring, as before indicated, insures positive engagement of the friction balls with the tubing. Attention is further called to the fact that in some instances it will be desirable to force the tool entirely through the tubing so that the balls will engage the lower end of the latter as shown in Fig. 1, this being done to obtain a more effective grip.

From the foregoing description and drawings, it is evident that I have evolved and produced a unique tool for use in wells for removing casings and other tubular members, the same being such that it can be readily lowered into the element to be removed to grip it at any desired point. Not only is the weight of the ball carrier depended upon to force the balls into engagement with the tubing, but a spring is employed to act in conjunction therewith to insure a positive grip of the balls by exerting a downward pressure on the carrier. Furthermore, when the parts are inverted as illustrated in the first two figures of the drawings, the tool is capable of being thus effectively used for the purpose of preventing tubing from dropping as clearly described. Particular emphasis is to be again laid on the aforesaid spring which serves to support the ball carrier in a floating state or in a position where the balls are readily susceptible to obtaining an effective grip on the stationary well casing if the tubing should accidentally drop. These and other advantages and features of the invention have doubtless been made apparent and for this reason a more lengthy description is deemed unnecessary.

Since probably the best result may be obtained with the construction and arrangement herein shown and described, this is

taken as the preferred embodiment of the invention. However, I wish it to be understood that minor changes coming within the scope of the invention as claimed may be resorted to if desired.

I claim:—

1. A well fishing tool comprising a longitudinally bored body formed at one end with a conical portion, piping threaded into said bore, said piping constituting a guide, a coupling associated with the piping, said coupling constituting a shoulder, a carrier slidable on the piping and surrounding said body, said carrier being formed with openings at one end, friction balls disposed in said openings and adapted to contact said conical portion of the body, and a spring surrounding a portion of the piping between the carrier and coupling for exerting pressure on the carrier to insure an effective grip of the balls on the part to be removed from the well.

2. A tubing catcher comprising a bored body adapted to be connected at its opposite ends to the adjacent spaced ends of two sections of piping of the tubing, said body being formed with an expanding conical surface, friction gripping balls in contact with said surface, and a substantially tu-

bular carrier for said balls surrounding the aforesaid body and provided with circumferentially spaced apertures in which the balls are arranged, said carrier being adapted to be slidably mounted on the tubing.

3. A well tubing catcher comprising a comparatively large coupling for connecting the sections of the piping in the tubing together, said coupling having a portion of its exterior shaped to provide a substantially conical expander having its smallest end disposed downwardly, a substantially cup-shaped ball carrier closed and flattened at one end, said carrier being provided at its open end with a row of circumferentially spaced openings, friction gripping balls arranged in said openings and adapted to be projected therethrough to grip a stationary well casing, said balls being in rolling contact with said expander, and a spring for acting on the lower flat end of said carrier for supporting the latter in a substantially floating state to render the balls susceptible to readily gripping the well casing when acted on by said expander.

In testimony whereof I have hereunto affixed my signature.

CHARLES A. BRUST, JR.
